COMB

Leonard R. Marsano, 3581 Cumberland Ave.,
Berkley, Mich. 48072

Filed June 9, 1966, Ser. No. 2,633

Term of patent 14 years

(Cl. D86—8)

FIG. 1 is a side elevational view of a comb embodying my new design.

FIG. 2 is an end view of the comb.

FIG. 3 is a top view of the comb.

FIG. 4 is a sectional view taken along the line 4—4 in FIG. 1.

FIG. 5 is a sectional view taken along the line 5—5 in FIG. 1.

The dominant features of my design reside in the portions shown in full lines.

I claim:

The ornamental design for a comb, substantially as shown and described.
